UNITED STATES PATENT OFFICE.

JAMES M. HINES AND JOHN S. BARNER, OF ALBANY, NEW YORK.

SLACK-ADJUSTER.

No. 890,277.

Specification of Letters Patent.

Patented June 9, 1908.

Application filed January 28, 1908. Serial No. 413,014.

To all whom it may concern:

Be it known that we, JAMES M. HINES and JOHN S. BARNER, citizens of the United States, residing at Albany, in the county of Albany and State of New York, have invented certain new and useful Improvements in Slack-Adjusters; and we do hereby declare the following to be a full, clear, and exact description of the invention, such as will enable others skilled in the art to which it appertains to make and use the same.

The object of the invention is to provide a simple and effective mechanism for automatically taking up in a brake-applying system the slack due to the wear of the brake shoes, the stretching of the brake-rods, etc. The nature of the means employed to this end will be understood from the following description and the accompanying drawings.

In the drawings, Figure 1 is a sectional elevation of a four-wheeled truck equipped with the improved mechanism; Fig. 2, is a detail plan view of the equalizing or floating lever and release spring and connections; Fig. 3 is a side elevation on a larger scale of the dead lever showing the gravity friction-grips and a portion of the adjusting-rod; Fig. 4 is an end elevation of the same parts; Fig. 5 is a plan view of the upper end of the dead lever and the gravity friction-grip attached thereto; and Fig. 6 is a sectional plan of the same lever showing the second gravity friction-grip.

Referring to Fig. 1, the upper brake-rod A extends from the upper end of the live lever 35 B to the floating or equalizing lever C (see Fig. 2). From this lever the rod A' extends to the brake cylinder lever, and from the end of the floating lever C opposite the end to which the rod A is attached the hand-brake rods E extend. In connection with this mechanism which is of common construction, and for the purpose of returning the live lever to its full release position is employed a coiled retracting spring F extending 45 from the floating lever C between the rods A and A' to a fixed hook f depending from the vehicle body. The lower ends of the live and dead levers are connected together by the rigid lower brake rod H and the live and dead 50 levers are pivoted in the struts of their respective brake beams.

The mechanism thus far described is sufficient, in connection with the brake cylinders, to apply and release the brakes, but for the 55 purpose of taking up the slack in the system automatically, mechanism is provided which

will now be described. An adjusting rod *a* is connected to the live lever by a suitable pin which passes through the elongated slot *a'*. The other end of the rod *a* passes through a gravity friction-grip comprising lever-arm *b* which is fulcrumed on the dead lever and is provided with a gripping collar *b*² through which the adjusting rod passes and a guiding extension *b'*. On the adjacent extra transom of the truck is a swiveled support *c* to which is pivoted the forked end of the take-up bar *d*, and this take-up bar passes through the gravity friction-grip comprising lever-arm *e* which is pivoted to the upper end of the dead lever and has the gripping collar *e*² through which the take-up bar passes and the guiding extension *e'*. From the end of the guiding extension *e'* rise the cheek pieces *f'* between which the take-up bar makes a fairly close fit, thus preventing a lateral displacement of the free end of the take-up bar with respect to the axis of the hole through the friction-grip. Such lateral displacement is likely to occur if the dead lever is inclined, and if means were not provided for preventing the displacement, there would be a tendency for the grip to bind on that account. The upper surface of the guiding extension serves to prevent the turning of the friction grip on its pivot in a counter-clockwise direction, as viewed in Fig. 1, and thereby insures a free movement of the grip along the take-up bar to the right, while allowing a gripping action in the other direction of movement. The guiding extension *b'* of the grip *b* is similarly provided with cheek pieces *g* and has a similar function.

The operation of these parts is as follows: On an application of the brakes the pull on the upper brake-rod A moves the brakes toward the wheels through the live and dead levers and the lower brake-rod H. During the portion of this movement which is necessary to apply the brakes when there is no slack in the system the pin on the live lever moves freely in the slot *a'* on the end of the adjusting-rod *a*, and does not affect the take-up mechanism. If there is any slack in the system it will be necessary to further move the live lever in order to bring the brake-shoes into engagement with the wheels and this further movement of the live lever brings the pin into engagement with the end of the slot *a'* and pulls the adjusting-rod, thereby turning lever-arm *b* on its fulcrum until the guiding extension engages the under side of

the adjusting rod, allowing the adjusting rod to slide through the gripping collar b^2 and thereby effecting an elongation of the adjusting-rod between the live and dead levers and 5 changing its reach. On the release of the brakes the live lever is returned to its normal position and moves freely until the pin engages the other end of the slot a' whereupon the adjusting-rod is forced, in the direction of 10 the dead lever, and lever-arm b , due to the combined effect of this movement and gravity (or gravity and a spring connection, as indicated in Figs. 3 and 4) turns on its fulcrum, causing collar b^2 to grip the adjusting rod, so 15 that the adjusting-rod cannot slide in that direction through the friction grip, and the return movement of the live lever in excess of the length of the slot a' tends to turn the dead lever in a direction to move the grip ful- 20 crumed on the upper end thereof along the take-up bar, by an action corresponding to that just described, thereby taking up the slack in the system. On the return move- 25 ment of any subsequent application of the brakes, movement of the friction grip along the take-up rod is prevented by the locking action of the gripping-collar e^2 , so that a new fulcrum for the system is established. It 30 will be seen, therefore, that by the arrangement of parts illustrated and described, the friction grips are normally in such a position as to have a holding grip on the adjusting rod (or take-up bar as the case may be) and if the movement is in one direction the grip is 35 turned on its fulcrum until the guiding extension engages the rod, whereupon the grip is released and rod moves freely through the gripping collar, whereas if the movement is in the other direction the gripping collar is 40 locked in engagement with the bar.

Ordinarily and particularly in heavy equipments, the weight of the friction-grips is sufficient to give the necessary holding gripping effect at all times, but sometimes, 45 and particularly on lighter equipments, a rattling of these parts may occur, and for the purpose of preventing this the spring connection h (see Figs. 3 and 4) between the friction grips b and e may be provided, the connec- 50 tion being such that the spring tends to turn the grips on their pivots into locking position.

It will be observed that this slack take-up mechanism is an extremely simple one, com- 55 posed of a few number of parts which may be easily and cheaply constructed, and it has the advantage of taking up at all times precisely the necessary amount of slack, an effect which does not exist where ratchet mechan- 60 ism is used, since no slack is taken up in the ratchet mechanism, unless the movement is sufficient to move the pawl over one complete notch.

What I claim is:

1. The combination with brake applying

and releasing mechanism, including primary and secondary brake applying levers and a connecting brake rod therefor, of means for automatically taking up the slack in said mechanism, comprising an adjusting rod 70 connected to one of the brake applying levers by a lost-motion device having a range equivalent to the normal movement of the brake shoes on application and release, mechanism connecting the adjusting-rod to the 75 other brake applying lever adapted to permit a relative movement between the adjusting-rod and said lever on an excessive application-movement of the brakes and to prevent such relative movement on release, 80 whereby the reach of the adjusting rod is changed in proportion to the slack in the mechanism, a take-up bar, and mechanism for adjustably connecting the secondary lever to the take-up bar, comprising a lever- 85 arm fulcrumed on the secondary lever and a gripping collar carried by said arm through which the take-up bar passes, and which is normally held in gripping engagement with the bar by the turning of the lever-arm on 90 its fulcrum, whereby the adjusting-rod, by virtue of its changed reach actuates the secondary lever to take up the slack in the system; substantially as described.

2. The combination with brake applying 95 and releasing mechanism, including primary and secondary brake applying levers and a connecting brake rod therefor, of means for automatically taking up the slack in said mechanism, comprising an adjusting rod con- 100 nected to one of the brake applying levers by a lost-motion device having a range equivalent to the normal movement of the brake shoes on application and release, mechanism connecting the adjusting-rod to the other 105 brake applying lever adapted to permit a relative movement between the adjusting-rod and said lever on an excessive application-movement of the brakes and to prevent such relative movement on release, whereby 110 the reach of the adjusting-rod is changed in proportion to the slack in the mechanism, a take-up bar, and mechanism for adjustably connecting the secondary lever to the take- 115 up bar, comprising a lever-arm fulcrumed on the secondary lever, a gripping collar carried by said arm through which the take-up bar passes, and which is normally held in grip- 120 ping engagement with the bar by the turning of the lever-arm on its fulcrum, and a stop which limits the turning of the lever-arm on its fulcrum in one direction only to permit the gripping collar to move freely on the take-up bar in that direction, whereby the 125 adjusting rod, by virtue of its changed reach actuates the secondary lever to take up the slack in the system; substantially as de- scribed.

3. The combination with brake applying 130 and releasing mechanism, including primary

and secondary brake applying levers and a connecting brake rod therefor, of means for automatically taking up the slack in said mechanism, comprising an adjusting-rod connected to one of the brake applying levers by a lost-motion device having a range equivalent to the normal movement of the brake shoes on application and release, a lever-arm fulcrumed to the other lever; and a gripping 10 collar carried by said lever-arm and through which the adjusting-rod passes, whereby a relative movement between the adjusting rod and the friction grip on an excessive application-movement of the brakes is permitted, and such relative movement on release is prevented, to thereby change the reach of the adjusting-rod in proportion to the slack in the system, a take-up bar, and mechanism for adjustably connecting the 15 secondary lever to the take-up bar comprising a lever arm fulcrumed on the said lever, and a gripping collar carried by said arm, through which the take-up bar passes, and which is normally held in gripping engagement with the bar by the turning of the lever-arm on its fulcrum, whereby the adjusting-rod, by virtue of its changed reach, actuates the secondary lever to take up the slack in the system; substantially as described.

4. The combination with brake applying and releasing mechanism, including primary and secondary brake applying levers and a connecting brake rod therefor, of means for automatically taking up the slack in said mechanism, comprising an adjusting-rod connected to one of the brake applying levers by a lost-motion device having a range equivalent to the normal movement of the brake shoes on application and release, a lever arm fulcrumed to the other lever, and a gripping collar carried by said lever-arm and through which the adjusting-rod passes, whereby a relative movement between the adjusting-rod and the friction grip on an excessive application-movement of the brakes is permitted, and such relative movement on release is prevented, to thereby change the reach of the adjusting rod in proportion to the slack 50 in the system, a take-up bar, and mechanism for adjustably connecting the secondary lever to the take-up bar comprising a lever arm fulcrumed on the secondary lever and a gripping collar carried by said arm through which the take-up bar passes, and which is

normally held in gripping engagement with the bar by the turning of the lever-arm on its fulcrum, whereby the adjusting-rod, by virtue of its changed reach, actuates the secondary lever to take up the slack in the system, and a spring connection between said lever-arms at opposite sides of their fulcrums; substantially as described.

5. A gravity friction grip for connecting the parts of slack take-up mechanism for 65 brake systems, comprising a lever-arm fulcrumed on one of the connected parts, a gripping collar carried by said lever-arm and through which the other connected part passes, and a guiding extension from the said 70 lever-arm having the cheek pieces f' ; substantially as described.

6. The combination with brake applying and releasing mechanism, including primary and secondary brake applying levers and a 75 connecting brake rod therefor, of means for automatically taking up the slack in said mechanism, comprising an adjusting rod connected to one of the brake applying levers by a lost-motion device having a range 80 equivalent to the normal movement of the brake shoes on application and release, mechanism connecting the adjusting rod to the other brake applying lever adapted to permit a relative movement between the adjusting rod and said lever on an excessive application movement of the brakes, and to prevent such relative movement on release, whereby the reach of the adjusting rod is changed in proportion to the slack in the 85 mechanism, a take-up bar supported on a universal joint, and mechanism for adjustably connecting the secondary lever to the take-up bar, comprising a lever arm fulcrumed on the secondary lever and a gripping 90 collar carried by said arm through which the take-up bar passes and which is normally held in gripping engagement with the bar by the turning of the lever arm on its fulcrum, whereby the adjusting rod, by virtue of its changed reach actuates the secondary lever to take up the slack in the system; substantially as described.

In testimony whereof we affix our signatures, in presence of two witnesses.
